(57) **CLAIM**

We claim the ornamental design for a laptop-type computer,
as shown and described.

DESCRIPTION

FIG. 1 is a top, front, right perspective view of the claimed
design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines shown in the drawings represent unclaimed
portions of the laptop-type computer and form no part of the
claimed design.
